Primary Examiner — Susan Bennett Hattan*Assistant Examiner* — Marie Fast Horse(74) *Attorney, Agent, or Firm* — Carter, DeLuca, Farrell & Schmidt, LLP(57) **CLAIM**

The ornamental design for an input device for a robot, as shown and described.

DESCRIPTION

FIG. 1 is a rear, perspective view of an input device for a robot in accordance with an embodiment of the present design;

FIG. 2 is a right side view of the input device for a robot of FIG. 1;

FIG. 3 is a left side view of input device for a robot of FIG. 1;

FIG. 4 is a top view of the input device for a robot of FIG. 1;

FIG. 5 is a bottom view of the input device for a robot of FIG. 1;

FIG. 6 is a front view of the input device for a robot of FIG. 1; and,

FIG. 7 is a rear view of the input device for a robot of FIG. 1.

(Continued)

The broken lines in the drawings depict parts of the input device for a robot that form no part of the claim.

1 Claim, 7 Drawing Sheets
